(57) **CLAIM**

The ornamental design for an LED lamp, as shown and described.

DESCRIPTION

FIG. 1 is a top, front and right side perspective view of an LED lamp, showing my new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded perspective view of the LED lamp shown in FIG. 1; and,

FIG. 10 is an enlarged view of portion 10 shown in FIG. 1. The dash-dash broken lines shown in the drawings illustrate portions of the LED lamp that form no part of the claimed design. The dot-dash broken line defines the boundary of the enlarged portions and form no part of the claimed design.
